UNITED STATES PATENT OFFICE.

WILLIAM VANSON DAWKINGS, OF WHITSTABLE, ENGLAND.

MIXING AND AERATING MACHINE.

1,384,383.

Specification of Letters Patent.

Patented July 12, 1921.

Application filed January 13, 1921. Serial No. 437,059.

To all whom it may concern:

Be it known that I, WILLIAM VANSON DAWKINGS, a subject of the King of Great Britain and Ireland, residing at 58 Canterbury road, Whitstable, in the county of Kent, England, have invented certain new and useful Improvements in Mixing and Aerating Machines, of which the following is a specification.

10 This invention relates to machines for mixing and aerating materials for the making of cakes, confectionery and the like.

The said machines as now constructed comprise a cylindrical or other pan or trough wherein the mixing of the materials is effected by a rotating beater having grids or blades radiating from a central stem. With such beaters it is found in practice that the air entrapped in the materials, and 20 which it is very desirable to retain therein, is to a great extent dissipated or forced out by the action of the grids or blades.

25 The object of this invention is to provide simple and convenient means for the accomplishment of the said mixing with the retention of the entrapped air and the thorough incorporation of the same with the materials under treatment.

30 The invention comprises the use of a beater provided with a series of slats or blades set at an angle with their path of motion or that of the materials to be mixed, such as will cause the said slats or blades to make a slanting progression through or 35 contact with the materials which become mixed and incorporated by the action of the inclined faces of the slats or blades.

Referring to the accompanying sheet of explanatory drawings:—

40 Figure 1 is a sectional elevation of one type of mixing machine having this invention applied thereto.

Fig. 2 is a sectional plan of the beater on the line A. B. of Fig. 1.

45 In the example illustrated the materials to be treated are placed in the pan or receptacle *a* adapted for rotation through the worm wheel *b* which is engaged by a worm mounted on the shaft *c*, the latter being 50 driven by belt *d* from the second motion shaft of the change speed gear box *e* at the upper end of the machine. The first motion

shaft of the said gear box (which is of any known type and therefore not fully shown in the illustration) is driven by belting running on pulley *f*. 55

The beater *g* having angularly disposed slats or blades as *h*, preferably formed integrally therewith, is fixed on the shaft *i* which is mounted on a bracket *j* carried by the boss or like part *k* of the machine framing. The said bracket *j*, which also carries the shaft or spindle *l*, can be rotated in the supporting boss or like part *k* by the hand wheel operated worm gearing at *m*. By such rotation of the bracket *j* the latter, together with the beater *g*, can be varied in position between the full line and dotted line positions shown at Fig. 1. 60

65 The rotation of the beater *g* is effected through the medium of the bevel gears shown at Fig. 1. The beater can be raised and lowered by means of the hand lever *n* which is connected by side links to the upper part of the beater spindle *i*. 70

75 The beater may be fixed or held stationary and the required relative movement of the materials under treatment obtained by the rotation of the pan or receptacle alone.

80 The beater may be in varying forms to meet varying requirements or types of machines, and provision may be made for adjusting the angularity of the beater slats or blades.

85 By the use of a beater constructed in accordance with this invention a very efficient mixing and aeration of the materials or ingredients is obtained without any violent distortion or disturbance of the same by the beater action. 90

Having thus described my invention what I claim as new and desire to secure by Letters Patent is:—

95 The herein described machine for mixing and aerating materials for cakes and like goods, consisting of a pan, a beater, means for rotating said pan and beater, and means for imparting axial and oscillatory movements to the said beater in the manner and for the purposes set forth. 100

In testimony whereof I have signed my name to this specification.

WILLIAM VANSON DAWKINGS.
